UNITED STATES PATENT OFFICE.

JAMES H. BULLARD, OF SPRINGFIELD, MASSACHUSETTS.

INSULATOR-PIN.

No. 828,481.

Specification of Letters Patent.

Patented June 12, 1906.

Application filed March 29, 1905. Serial No. 252,715.

To all whom it may concern:

Be it known that I, JAMES H. BULLARD, a citizen of the United States of America, residing at Springfield, in the county of Hampden and State of Massachusetts, have invented new and useful Improvements in Insulator-Pins, of which the following is a specification.

This invention relates to insulator-pins, and specifically to the construction of metal insulator-pins, the invention being in the nature of an improvement on the construction forming the subject-matter of Letters Patent of the United States issued to me on October 18, 1904, and numbered 772,553, the object of 15 the invention being to provide improved means for securing the insulators to the pins.

It has been found in practice that it is inconvenient and expensive to secure the insulators to the pins by means of a plastic substance poured into a cavity in the insulator to hold the latter securely to the end of the pin when the substance hardens, as this method necessitates an equipment which in the field is more or less cumbersome and 20 tends to retard the movements of the workmen who are sent out to equip the line after the poles have been set, and as the wires and cables frequently have to be installed over a rough country and under all weather conditions 25 some means of securing the insulators to the pins other than the manner described above have been sought. By means of the present invention the securing of the insulators to the pins can be effected by any one of 30 ordinary intelligence.

The invention is fully illustrated in the accompanying drawings, in which—

Figure 1 is a sectional elevation of an insulator-pin, showing the invention applied thereto, the insulator being also shown in section. Fig. 2 is a side elevation of the same viewed from a different point, the insulator being dotted in. Fig. 3 is a sectional view of the insulator-pin having the invention applied thereto, the plane of the section being on line 3 3, Fig. 2. Fig. 4 is a perspective view of the under side of a channeled washer or clamp member for the base of the pin. Fig. 5 is a side elevation of an insulator-pin, showing a modification of the construction shown in Figs. 1 and 2. Fig. 6 is a side elevation of an insulator-pin, showing the pins and the base made in one piece instead of separately, as in the preceding figures, and embodying 55 the same modification as is shown in Fig. 5.

Figs. 7 and 8 are respectively top and plan views of Figs. 5 and 6.

Referring to the drawings, in which like letters refer to like parts in the different figures, *a* indicates an insulator of ordinary construction, and *b* the longitudinally-disposed members constituting the pin and which may be made of metal bars bent up to suitable shape, as shown in Figs. 1 and 2, with the base portions thereof secured to a cross-bar *c* by means of a bolt *d* or otherwise, or, as shown in Fig. 6, these pin members may be cast integral with a base *e* and used in that form, or they may be made of malleable metal, if desired. The invention does not run to the pin construction or the method of securing the same to a cross-bar, for that forms the subject-matter of my said prior patent, this invention being directed to means for securing the insulator to a pin, of which that shown in my said prior patent is a good type.

In carrying this invention into effect the upper ends of the bars or pin members *b* may be made as shown in Figs. 1 and 2—that is, of two substantially V-shaped members secured by their bases to a suitable support—or they may be made of separate converging pin members, as shown in Figs. 5 and 6. Preferably, however, the pin is made of the bent-up pin members *b* shown in Figs. 1 and 2, and there is inserted between these members and in substantial axial alinement with the pin a block *f*, in cross-section having the form of a cross, the edges of the arms of which are provided with screw-threads *g*, adapted to engage a screw-threaded recess *h* in the insulator, the rectangularly-disposed arms of the block *f* extending beyond the peripheries of the converging ends of the pin members *b*, as shown clearly in the sectional view, Fig. 3, to the end that the screw-threads *g* on the block may engage with the threaded recess *h* when the insulator is screwed on. It will be observed, however, from an examination of Fig. 1 that the block *f* is made tapering and that these arms of the block which are located between the two separated V-shaped pin members *b* are tapered, one of these tapered portions being indicated by *j* in said Fig. 1, and the degree of the taper is such that as the insulator is screwed down on the pin and the inner end of the recess *h* comes to a bearing on the upper end of the pin members the further screwing up of the insulator will effect

- the spreading of the pin members by means of the drawing up of the tapered portion *j* of the block sufficiently to cause the pin members to come to a bearing against the edge of the screw-threads in the recess *h*, and thus bind the insulator tightly to the pin by the described wedging effect before the end of the block comes in contact with the upper ends of the pins, which being made in the form shown would render this locking action ineffective if the block came to a bearing first.
- If the pin members are separated one from another at the upper ends thereof, as shown in Figs. 5 and 6, the effect would be exactly the same as in the construction shown in Figs. 1 and 2, and it is immaterial which of the pin members are separated; but, as shown in the sectional views, Fig. 7 and 8, it is preferred to turn inwardly, as at *m*, Figs. 5 to 8, two adjacent ends of the pins to overhang the upper ends of oppositely-located cross-arms of the block *f*, the slightly-hooked ends of the pins serving to prevent the withdrawal of the block from between the converging ends of the pin members. Obviously, however, these converging ends of the pin members may be left straight instead of being made with their ends turned one toward the other, as at *m*.
- It is of course obvious that the insulator may be secured on the end of a pin constructed substantially as shown in Figs. 1, 2, 5, and 6, even though the block *f* were not wedge-shaped, and therefore would not spread the ends of the pins to bind the same against the wall of the recess *h*, and a construction of this character would fall within the scope of the invention; but the preferred construction is that which has been described herein.
- Having thus described my invention, what I claim, and desire to secure by Letters Patent of the United States, is—
1. An insulator-pin comprising a plurality of pin parts longitudinally disposed, on the free ends of which an insulator may be secured, and means to secure the insulator to the pin consisting of a slideable member fitted between the free ends of the pin with which member the insulator has a screw engagement, and means to secure the pin parts on a suitable support.
2. An insulator-pin consisting of a plurality of separated individual pin members the ends of which converge to receive an insulator, a tapered screw-threaded member movably located between said converged ends, the insulator being provided with a screw-threaded recess to receive said tapered member whereby in screwing the insulator on said member, the converged ends of the pin members may be separated to secure the insulator on the pin.
3. An insulator-pin consisting of a plurality of separated individual pin members, the converged ends of which constitute a support for an insulator, a screw-threaded member movably located between these ends, and means to limit the movement thereof toward the end of the pin, together with an insulator having a screw-threaded recess to receive said member.
4. An insulator-pin consisting of two substantially V-shaped pin members, the converged apices of which constitute a support for an insulator, a tapered block, cross-shaped in cross-section, movably located between the ends of the pin members, the edges of the arms of said block being screw-threaded and extending beyond the sides of the pin members, whereby an insulator, having a threaded recess therein may be screwed onto said block to draw the latter toward the ends of the pin members to force them apart laterally against the wall of the recess in the insulator.
